UNITED STATES PATENT OFFICE.

DORR R. MARTIN, OF DETROIT, MICHIGAN.

OIL BURNER.

Application filed January 13, 1922, Serial No. 528,939. Renewed February 5, 1923.

This invention relates to oil burning devices for steam heating furnaces, steam boilers etc., and the object of the invention is to provide a simple, efficient and comparatively inexpensive automatically operated burner adapted to maintain the temperature of the boiler between predetermined high and low limits. A feature of the invention is involved in the means whereby the temperature of the oil flowing through the burner is maintained at a controllable uniform temperature practically unaffected directly by the heat of the burner. A further object of the invention is to provide, in conjunction with an oil burning device, a pilot light supplied by a gas line by means of which the oil may be ignited and through and by means of which the temperature of the inflowing oil is maintained uniform and also to provide in conjunction therewith means for cutting off the oil supply to the burner upon the pilot being extinguished. A further object of the invention is to provide, in conjunction with the burner, a device controlled by the pressure of the water of the boiler being heated, for stopping or starting the flow of oil in the burner. A further object of the invention is to provide, in conjunction with the burner, a means whereby the flow of oil in the burner may be stopped or started manually or thermostatically. The oil is supplied to the burner by means of an electric motor and a pump and the automatic control devices are utilized to make or break the circuit of the motor thus starting or stopping the flow of oil through the burner. Other specific details of the invention and objects and novel features thereof are hereinafter more fully described and claimed and the preferred form of a burner structure embodying my invention is shown in the accompanying drawings in which—

Fig. 1 is a section taken on line 1—1 of Fig. 2 showing my improved oil burner.

Fig. 2 is a plan view thereof.

Fig. 3 is an elevation of part of the control mechanism.

Fig. 4 is a section taken on line 4—4 of Fig. 3.

Fig. 5 is an enlarged detail showing the oil channel or conduit and the chamber in which it is housed.

Fig. 6 is a diagram showing the burner, boiler, motor, pump and thermostat.

The burner consists of a casing 1 containing the control parts and oil conduit and heating chamber therefor at the forward end of which is the oil discharge nozzle 2. This nozzle 2 discharges through a centrally apertured cone shaped member 3 about the open end of which is another somewhat similar shaped member 4 providing a mixing chamber, there being a space 5 provided between the two members 3 and 4 at the rear of the open end of the member 3 through which air may flow to provide the necessary oxygen for the burning of the oil discharged through the nozzle and member 3. This member 4 may be supported in a cylindrical or other shaped member 6 which may be fastened directly to an aperture, for instance the door opening, of a furnace being provided with a flange 7 having apertures for reception of bolts to secure the members 6 in place. The casing 1 is supported on the member 6 by a series of bolts 8 as will be understood from Figs. 1 and 2 which hold the member 1 and the forward flange 9 thereof properly spaced relative to the rear open end of the member 4. The air flow may be varied by means of these bolts 8 to bring the member 1 and flange 9 thereof nearer or farther from the rear end of the member 4 as may be required to supply the necessary air for combustion. The member 1 has a chamber 10 in the forward part thereof, the forward end of which is closed by a cap plate 11 secured thereto in a manner to seal the chamber. The nozzle 2 is provided in this cap 11 and in addition to this nozzle is provided with a conduit 12 to which the oil conduit 13 is secured in a manner to prevent leakage of oil within the chamber 10. A member 53, forming a drip-page cup below the nozzle 2, is provided on the cap plate 11 and also acts as a deflector for the pilot flame. Due to the heat to which the cup is subjected, oil may not accumulate therein and drippage from the burner is prevented. This oil conduit 13 in the chamber 10 is preferably in the form of a cylindrical coil, the discharge end of which is connected with the conduit 12. It is to be noted that the rear end of the coil is connected with the conduit 12 and the forward end of the coil extends to the rear where it passes out through the wall of the chamber 10, as will be readily understood from Fig. 2 and is

there provided with a packing nut 14 to prevent leakage from the chamber. This chamber has a water supply line 15 and a discharge line 16 opening thereinto from the opposite side as will be understood from Fig. 1. Both water supply line 15 and discharge line 16 are provided with valves as indicated in Fig. 1 designed to regulate the flow of water to and from the chamber 10. 5 The supply line should be connected with the boiler near the bottom of the water space and the line 16 should be connected with the water space of the boiler above the point of connection of the line 15 being in such 10 relation that water may naturally flow through the chamber 10 due to difference in temperature of the water in the lines 15 and 16. The conduit 12 and coil of the oil line heretofore mentioned, being in the chamber 15 15 20 25 30 35 40 45 50 55 60 65 70 75 80 85 90 95 100 105 110 115 120 125 130

The conduit 12 and coil of the oil line heretofore mentioned, being in the chamber 10 are subject to the temperature of the water of the boiler and the oil is therefore at a practically uniform temperature as discharged through the nozzle 2. However, this uniform temperature may be regulated as required by the means of adjusting pilot flame and the valve in the water supply line 15 and discharge line 16, I having found that various grades of oil require different temperatures to secure the best results. The flame of the burner is forward of the open end of the shield 3 and thus is at a point distant from the oil conduit and chamber 10 and therefore the flame of the burner does not materially affect the temperature of the oil in the conduit. Heretofore, it has been the practice to heat the oil for the burner usually by the influence of the heat or flame of the burner but as this varies considerably, such arrangement has proven unsatisfactory, a more efficient and economical result being attained by holding the oil at practically a uniform temperature. I have found it desirable to hold the oil practically at the desired temperature even when the burner is not in operation in order that when the burner starts to operate the oil will be in the best condition to produce the proper flame.

The burner is automatic in its operation—that is, upon a certain low pressure of the boiler being attained or a certain low temperature of the thermostat being attained, the burner will start into operation, the oil being started flowing through the coil 13 and nozzle 2. This is ignited by the pilot light indicated at 17 which is fed by a gas line 18. This pilot burner projects its flame around and past the member 42 and inlet pipe 15 through a chamber 19 formed in the casing 1 and into the shield member 3 very close to the point of discharge of oil from the nozzle 2. It will be understood from the position of the pilot burner that the projection of the pilot flame is at an angle to the direction of oil flow through the nozzle 2. It will further be noted that the water line 15 of

the chamber 10 lies directly in the path of this pilot flame which is to be understood to be normally burning. Thus the water in the pipe 15 will be heated and this will tend to cause a flow of water through the chamber 10 even when the oil burner is not in operation. This will maintain the oil in the oil conduit and coil at proper temperature for securing the most efficient result in combustion. When the burner is in operation and the water of the boiler heated, the flow through the chamber 10 continues and, due to the chamber 10 being open to the boiler, the pressure of the boiler affects the pressure in the chamber 10 and this pressure is utilized to control the starting or stopping of the oil flow—that is, when the pressure has reached the desired maximum point the oil flow is to be stopped and when the pressure in the boiler has reached the minimum the oil flow is to be started and this is accomplished in the following manner:

As heretofore mentioned and as is usual with burners of this general type and as indicated in the diagram Fig. 6, an electric motor 60 is utilized in the operation of a pump 70 to force the oil under pressure through the oil line and nozzle. The oil is projected forward of the shield 3 and through the forward end of the member 4 being ignited by the pilot flame from the pilot burner 17 as heretofore stated. Part of the electric circuit for the motor is indicated at 20 and 21, which lines lead into a switch member 22 at the rear upper side of the casing 1. This switch is of the ordinary lever type indicated more clearly in Fig. 3 by dotted lines and these two lines 20 and 21 lead into the switch case to terminals 23 and 24 respectively which may be closed by a contact member 25 on an arm 26. This switch is of a common type now on the market and the arm 26 is provided with a spring (not here shown) which tends to withdraw the member 25 from engagement with the contacts 23 and 24. A button or push rod 27 is provided for the switch by depression of which, from the position shown in Fig. 1, the circuit between the line 20 and 21 is closed and the motor energized and, when released to action by the spring, the lever 26 moves to the position shown in Fig. 1 breaking the circuit and stopping the motor, it being remembered that the starting of the motor causes oil to be discharged through the nozzle 2 and the stopping of the motor causes cessation of such discharge of the oil.

To automatically control the stopping and starting of the motor in order to maintain the temperature influencing the thermostat or the pressure of the boiler within the desired ranges, I have provided a bellows member 28 which is the usual known type of deeply corrugated metal cylinder that may expand or contract under variations in pres-

sure. The base of this corrugated bellows member has an apertured hub 29 open to the chamber 10. The opposite end of the bellows is closed and is provided with an 5 outwardly projecting lug 30, this lug riding in a trunnion 31 provided in a bracket in the interior of the chamber 80 for the bellows member. It will be seen from this arrangement that the interior of the member 28 is 10 open to the chamber 10 and upon an increase in pressure, due to pressure of steam, the bellows member 28 will be caused to expand which is the condition of the device in Fig. 1.

15 I have utilized this bellows member 28 to control the switch 22 and for this purpose I have provided a lever 32 secured on the cross shaft 33 pivotally mounted at the rear end of the casing 1. This lever is shown in side 20 elevation in Fig. 1 and in front elevation in Fig. 3. It will be observed from these two figures that the said lever 32 extends upward from its pivotal shaft support and terminates just forward of the push rod 27 of the 25 switch against which it may engage. It will be observed more particularly from Fig. 3 that the member 30 of the bellows device engages against the lever between the shaft and its extremity and that, upon pressure being exerted in the member 28, the switch lever will be moved outward to position shown in Fig. 1 allowing the spring of the switch to project the push rod and break the electric circuit to the motor. This stops the oil 30 flame due to the fact that oil is not discharged through the nozzle upon the stopping of the motor and thus when the pressure of the boiler is sufficiently high, oil is automatically cut off from the burner and in 35 order to start the burner into operation the push rod 27 must be depressed closing the circuit to the motor.

40 I have provided for the starting of the motor upon predetermined reduction of pressure in the boiler in the following manner—The shaft 33, which provides the pivotal support of the switch control lever 32, is pivoted in bearings in the casing in which it may turn and further, as hereinafter shown, in which 45 the shaft may move longitudinally. On the outer side of the casing, as will be understood from Figs. 2 and 3, the shaft has rigidly attached thereto a forwardly extending lever 34, the forward end of which is provided with an eye to receive the hook 35, which hook has a stem depending therefrom sustaining the weights 36, a greater or less number of which may be supported on the said hook member to increase or decrease the 50 pressure tending to turn the shaft 33 and switch control lever 32 thereon. By this arrangement it will be seen that, as the pressure decreases in the boiler and consequently in the chamber 10 and bellows member 28, 55 it will reach a point where it is overcome by

the weighted arm 34. This causes the lever 32 to move forward to the right of the position shown in Fig. 1 depressing the push rod 27 of the switch and closing the electric circuit to the motor which, upon starting 70 operation, causes flow of oil under pressure through the nozzle 2. This is automatically ignited by the pilot light and the motor will continue to run during the time the push rod is depressed and the motor circuit 75 closed.

With the operation of the apparatus as described herein, the motor switch is closed by the weighted lever and is opened by pressure of the water in the chamber 10 and in 80 the boiler. A room whose temperature is to be regulated might not be heated to the requisite degree at the time a comparatively high pressure had been attained in the boiler.

I have therefore provided in conjunction 85 with the weighted lever a thermostat indicated at 90 in Fig. 6 which is of the usual type controlling the lever 101 of an ordinary thermostat motor located at any convenient point usually distant from the thermostat. 90 The movement of the lever 101 is such with reference to the thermostat that it moves to the position indicated in full lines in Fig. 6 when the temperature of the room influencing the thermostat is at a predetermined 95 high point and moves to position indicated in dotted lines in Fig. 6 when the temperature of the room falls to a predetermined point. This lever 101 is connected with the eye of the lever 34 of the burner by means 100 of a cable or other adaptable device 102 so that the relative operative and inoperative positions of the two levers 34 and 101 are synchronous—that is, when the temperature of the room by which the thermostat is influenced rises to a predetermined point the burner will be shut off and when it drops to a 105 predetermined point the weighted lever will be dropped and the burner turned on as heretofore described. In conjunction with this 110 well known type of thermostat and thermostat motor the bellows member 28 really becomes a safety factor preventing too high pressure being attained in the boiler before the temperature of the room reaches the desired high degree. In the event the pressure in the bellows reaches its high point before the temperature of the room has risen to the high point the bellows member 28 would act 115 to break the motor circuit and stop the flame irrespective of the condition of the thermostat and thermostat motor, but when the temperature of the room has reached the high point the thermostat motor would operate to raise the weighted lever 34 and hold the electric motor circuit broken, stopping the flame. Under this condition the flame 120 will not be started until the thermostat and its motor act to drop the weighted lever and close the circuit for the electric motor. By 125

130 65 it will reach a point where it is overcome by

this general arrangement of parts the burner is made automatic in its operation and therefore starting and stopping the flame of the burner as the pressure of the boiler is low or high or as the temperature influencing the thermostat is low or high. The range of pressure within which the burner may operate is determined by the amount of weight with which the arm 34 is provided. One of the sources of failure of previously known oil burning devices for furnaces is obviated in that there is no possibility of oil flowing after the flame is extinguished as the oil line is completely released from pressure to extinguish the flame. Any drippage occurring upon stopping the motor is caught in the cup 55 and, as the cup is hot, such drippage is immediately vaporized. The oil pressure is produced by the pump operated by the motor and the oil will burn as long as there is any discharge thereof due to the fact of the discharge being directly into and through the flame of the pilot light.

Another source of trouble with ordinary oil burning devices arises through possible operation of the pump and motor when the pilot light is extinguished and if that should happen the oil may be discharged without being ignited. To avoid this difficulty I have provided a peculiar structure to prevent the operation of the device if the pilot light is out. This is arranged in the following manner—In the structure here shown I have provided an expansible bellows member 40 in Fig. 1 which is filled with a volatile fluid and is similar in general respects to the bellows member 28 but considerably smaller than the said member. The base of this bellows member 40 is mounted as indicated at 41 directly on the side of the casing 1. The rear end of this member 40 has a rod 42, the terminal end of which is bent to lie in the path of the pilot flame. This member 42 therefore is heated by the pilot flame and the heat, by reason of the rod being attached directly to the base of the bellows member 30 is conducted directly to the volatile fluid within the member 40 causing the same to expand. The forward end 43 of this bellows member is provided with a tubular extension 44 in the open end of which is mounted a plug 45 having a slot 46 therein through which a pin 47 extends supporting the same in place and allowing some latitude of movement of the tube relative to the plug 45. A spring 48 is provided tending to project the plug outwardly from the tube 44. It is to be noted that the switch control lever 32 is secured to the shaft 33 and as before stated, the said shaft 33 is capable of longitudinal movement in its bearings in the casing 1. The hub of the member 32 is elongated extending a short distance longitudinally of the shaft and is provided with a circumferential groove 49 in which the end

of the plug 45 normally lies. A coiled spring 50 is provided on the shaft engaging between the hub of the control lever 32 and the case and this spring tends to move the shaft to the right of the position shown in Fig. 3 and is normally prevented from so moving the shaft by the plug 45 engaging in the groove 49 which is its position when the pilot light is burning. Should the pilot light go out for any cause the volatile fluid in the bellows 40 would condense and the bellows member would normally, due to its structure tend to contract and to finally withdraw the plug 45 from its groove in the hub of the control member 32. The slip connection of the plug in the tube 44 permits the member to expand and contract within certain limits without actuating the plug.

Withdrawal of the plug from its groove permits the spring 50 to force the shaft 33 and the lever 32 fixed thereto to the right of the position shown in Fig. 3 and this brings the upper end of the control lever 32 out of contact with the end of the push rod 27 of the switch and permits the push rod, due to action of the spring of the switch, to project outwardly to the position shown in Fig. 1 breaking the supply circuit for the motor and stopping operation of the burner until the parts are restored to normal position. These parts may be restored to normal position by lighting the pilot light through heating the rod 42 which will cause the bellows member 40 to expand tending to project the plug 45 whereupon the lever 32 and its rod may be moved to the left to position to allow the plug 45 to enter its groove 50 and to hold the parts in their normal position. In order that the lever 32 in its movement to the right by action of the spring 50 may not be brought out of operative relation with the member 30 of the bellows member 28, I have provided a side extension 52 thereon so that, whatever the position of the lever 32, it is always contacted by the member 30 and in position to be actuated thereby.

The chamber 10 is here shown as connected with the water space of the boiler but evidently the chamber may be connected with a source of supply separate from the boiler if desired and liquid other than water may be supplied thereto which will be heated by the pilot light directed against the conduit 15 for the liquid adjacent the chamber. This liquid or water in the chamber has a double function—namely, that of heating the fuel conduit in the chamber and of maintaining the temperature of the nozzle below the carbonizing temperature of the fuel. As shown particularly in Fig. 5, this nozzle is provided in the forward wall of the chamber 10 and water or other liquid in the chamber absorbs the heat from this forward wall and

nozzle caused by the burning of the fuel at the nozzle and the temperature at which the nozzle may operate will depend very largely upon the distance the discharge point of the 5 nozzle is from the forward wall 11 of the chamber. If it is desired that the nozzle should operate at a temperature closely approaching the carbonizing point of the fuel, it may be a greater distance from the forward wall 11 than as shown in the drawing—that is, in a burner adapted for use in a boiler of the character ordinarily utilized in household heating systems, I have found that a nozzle approximately four inches in 10 length will become heated at the discharge end approximately to the carbonizing temperature of kerosene. Therefore, for such purpose the fuel nozzle is preferably not more than two inches in length and may be 15 formed considerably less in length directly in the forward wall 11 and still secure an efficient result. By providing means for preventing carbonizing of the fuel at the nozzle, and choking of the fuel line by deposition 20 of matter therein by influence of high degrees of heat, I have secured a highly efficient burner requiring little or no attention of the operator and eliminated the cause of failure found in many well known fuel oil 25 burners.

From the foregoing description it is evident that the objects of the invention are achieved; that the burner is automatic in operation and controlled by the temperature 30 at the thermostat or by the pressure in the boiler and that the burner is automatically rendered inoperative in case the pilot is extinguished or the pressure reaches a predetermined maximum point. It is further evident 35 that the device is highly efficient in operation due largely to the fact that means is provided to maintain the oil at an equable temperature; that means is provided to vary the air flow thus enabling the burner to be 40 adjusted to secure a flame of the highest thermal efficiency, and that the various objectionable features of oil burners heretofore used are eliminated.

Having thus fully described my invention, 45 what I claim and desire to secure by Letters Patent of the United States is—

1. In an oil burner, for furnaces having a water space, a casing having a chamber, the forward wall of which is provided with 50 an aperture, a nozzle member on the exterior of the said wall with which the said aperture is in communication, an oil conduit having a portion thereof enclosed within the chamber and connected with the said aperture of the front wall, a water supply conduit leading to and from the said chamber and connected with the water space of the furnace, a pilot light for the burner positioned to direct the flame thereof upon the 55 water conduit to maintain the temperature

of the water in the chamber practically constant, electrically operated means for supplying oil to the oil conduit, and automatic means actuated through influence of pressure of water in the chamber to control the 70 said electrically operated means.

2. In an oil burner, a casing having a chamber, an oil conduit having a portion within the chamber in the form of a coil, a discharge nozzle with which the said coil is 75 connected, a water supply line leading to and from the said chamber, a pilot light for the burner positioned to direct the flame thereof upon the water conduit whereby the temperature of the water in the chamber is 80 maintained at practically constant temperature, automatic means actuated through influence of pressure of the water in the chamber for controlling the flow of oil through 85 the conduit.

3. In an oil burner for steam boilers and the like comprising the combination therewith, of a casing having a chamber, conduits to and from the chamber opening to the water space of the boiler, one of said lines connected with the water space near the bottom and the other connected with the water space thereabove, an oil conduit having a material part thereof located within the said chamber, an electric motor, a pump for discharging the fluid under pressure through the oil conduit, a pilot light for heating the water inlet to the chamber to maintain the water in the chamber at an equable temperature, a discharge nozzle at 90 the forward end of the casing with which the oil conduit is connected, the pilot light being positioned to project flame into the path of oil discharged from the nozzle, automatic means actuated by the pressure of water in the chamber to break the circuit to the motor and stop the flow of oil through 95 the nozzle, and automatic means for breaking the circuit to the motor upon the flame of the pilot burner being extinguished. 100

4. In an oil burner for a steam boiler, a casing having a chamber, an oil conduit having a portion thereof in the form of a coil within the said chamber, a nozzle with which the discharge end of the coil is connected and through which the oil may be discharged for combustion, a water supply line leading to and from the said chamber, a pilot light for the burner, the flame of which impinges on the water conduit whereby the temperature of water passing through the water chamber is maintained at practically constant temperature, the pilot light being further adapted to ignite the oil discharge from the conduit, said water supply line being 115 connected with the water space of the boiler being heated by the burner whereby the pressure of the boiler is imposed upon that of the chamber, an expandable and contractible bellows member open to the chamber and 120

- subject to the influence of the pressure thereof, an electric switch, means actuated by the bellows in expanding to open the switch, and means whereby upon contraction of the 5 bellows the switch is closed.
5. An oil burner for heating of steam boilers etc., comprising the combination with a boiler, an oil supply source and an electric motor and pump for causing flow of oil 10 under pressure, of a casing having a chamber, an intake line for the chamber connected with the lower part of the water space of the boiler, an outlet line for the chamber connected to the water space above the first 15 named line, an oil conduit having a portion thereof located within the said chamber subject to the temperature of the water passing therethrough, a discharge nozzle with which the said oil line is connected through which 20 the oil is discharged under pressure by means of the pump, an electric circuit for the motor, a switch in the circuit, a weighted lever tending to actuate the switch to close the circuit, an expansible member subject to influence of pressure of the water in the said chamber to actuate the lever to cause the switch to break the electric circuit.
6. An oil burner for the heating of steam boilers etc., comprising the combination with 30 the boiler, an oil supply source and electrically controlled means for causing the flow of oil under pressure, of a casing having a chamber, an intake line and a discharge line for the chamber connecting respectively with 35 a lower and a higher level of the water space of the boiler, an oil conduit through which oil is caused to flow by the electrically controlled apparatus, said conduit having a portion thereof located within the said 40 chamber subject to the temperature of the water passing therethrough, a discharge nozzle with which the said oil line is connected, a circuit for the said electrical apparatus, a switch for controlling the circuit, 45 said switch having a spring projected push rod normally opening the switch to break the circuit, a weighted lever having an end engaging the push rod, the weight thereof tending to close the switch against the tension of its spring, said lever being adapted 50 to be variably weighted for the purpose described, an expansible bellows like member open to the interior of the said water chamber of the burner and adapted by expansion 55 to retract the lever against the weight thereof to permit the spring to open the switch.
7. In an oil burner for heating steam boilers etc., the combination with the boiler, an oil supply source and electrically controlled means for causing flow of oil under pressure, of a casing having a chamber connected with the water space of the boiler to permit a flow of water through in the chamber, an oil conduit connected with the apparatus for causing the flow of oil, a nozzle 60 through which the conduit discharges, an electric switch for making and breaking the circuit of the electrically controlled apparatus, a weighted lever for actuating the switch to close the circuit, and an expansion bellows member adapted to expand by pressure of the water in the said chamber to actuate the lever and opening the switch to break the electric circuit. 70
8. In an oil burner for steam boilers etc., in combination with the boiler, an oil supply source, a conduit for the oil and electrically controlled means for causing flow of oil therethrough, of a casing having a chamber connected with the water space of the boiler in a manner to permit flow of water through the chamber, a nozzle with which the oil conduit is connected and through which the oil is discharged, a pilot light so positioned that the flame thereof may ignite 75 the oil as discharged from the nozzle, a switch for the circuit of the electrically controlled apparatus, automatic means whereby the switch may be opened upon pressure in the chamber reaching a predetermined 80 amount and closed upon pressure falling below a predetermined amount, means influenced by the heat of the pilot light to maintain the automatic means in operative relation, and means whereby when the pilot light is extinguished the said automatic means is in non-operative relation with the switch. 85
9. In an oil burner for steam furnaces etc., the combination with a boiler, oil supply 90 conduit and electrically controlled means for forcing oil under pressure therethrough, of a casing having a chamber connected with the water space of the boiler in a manner to permit flow of water through the chamber, a nozzle with which the oil conduit is connected, a pilot light positioned to ignite the oil on discharge through the nozzle, a switch for the circuit of the electrically controlled apparatus, an expansible bellows like member containing a volatile fluid adapted to be influenced by the heat of the pilot light, a switch for the circuit of the electrically controlled apparatus, a weighted operating lever for actuating the switch to close the electric circuit, means influenced by the pressure of the water in the chamber to cause the switch to open the circuit for the electrically controlled means, a spring tending to move the lever out of operative relation with the switch element, the expansion bellows member while under influence of heat of the pilot flame tending to hold the switch actuating lever in operative relation with the switch and upon contraction due to extinguishing of the flame to release the lever to operation by its spring to move the same to non-operation with the switch. 100
10. In an oil burner for steam boilers and the like, the combination with the boiler, 105

- an oil conduit and electrically controlled means for causing the flow of oil under pressure through the conduit, of a casing provided with a chamber connected with the water space of the boiler in a manner to permit flow of water therethrough, a switch in the circuit of the electrically controlled means, a switch control device, and means subject to pressure of the water chamber for controlling operation of the switch control device to open the switch, a weight tending to operate the switch control to close the switch upon reduction of pressure in the said chamber, means whereby the switch control device tends to move to non-operative position, a pilot light, and means actuated by the heat of the flame thereof to hold the switch control parts in operative relation with the switch.
11. In an oil burner for steam boilers and the like, the combination with the boiler, an oil conduit and electrically controlled means for causing a flow of oil under pressure through the conduit, of a casing provided with a chamber, said oil conduit passing through the chamber, a water conduit providing an inlet for the chamber connected with the lower part of the water space of the boiler, a water conduit providing an outlet for the chamber connecting with the water space of the boiler above the first named conduit, a valve in the said last named conduit, an electric circuit for the said electrically controlled means, a switch for opening or closing the circuit, a switch control device gravity actuated to close the switch, means subject to pressure of the water in the water chamber for actuating the switch control device to open the switch, and a pilot light positioned to maintain the water of the water chamber at practically uniform temperature and further adapted to ignite the oil discharged through the burner.
12. In an oil burner for steam boilers and the like, the combination with the boiler, an oil conduit, and electrically controlled means for causing flow of oil under pressure through the conduit, of a casing provided with a chamber, said oil conduit having a portion thereof in the said chamber, a water inlet and outlet for the chamber consisting of conduits connected with a low and high point respectively of the water space of the steam boiler, means for varying the volume of flow of water through the chamber, a pilot light positioned to maintain the water passing through the chamber at practically uniform temperature and further being adapted to ignite the oil discharged through the conduit, a switch by the opening or closing of which the electrically controlled means may be stopped or started, a switch control device gravity actuated to close the switch, and means actuated by pressure of

the water in the water chamber to open the switch.

13. In an oil burner for steam boilers and the like, the combination with the boiler, an oil supply source, a conduit for the oil and electrically controlled means for causing a flow of oil under pressure through the conduit, of a casing having a chamber connected with the water space of the boiler to permit a flow of water through the chamber, a nozzle with which the oil conduit is connected, a portion of the said oil conduit being located in the said chamber of the casing, a pilot light so positioned that the flame thereof may ignite the oil as discharged from the nozzle and further to maintain the temperature of the water flowing through the chamber at substantially uniform temperature, a switch for the circuit of the said electrical controlled means, automatic means whereby the switch may be opened upon pressure in the chamber reaching a predetermined amount, gravity actuated means for closing the switch upon pressure falling below a predetermined amount, and thermostatically controlled means by which the switch may be opened by influence of temperature of predetermined high degree.

14. In an oil burner for steam furnaces and the like, the combination with the furnace and electrically controlled apparatus for forcing oil through the burner to the furnace, of a pilot light located in the burner in position to ignite the oil as it is discharged, a switch for opening and closing the circuit of the electrically controlled apparatus, a switch control device gravity actuated to close the switch, means actuated by the steam pressure of the boiler to open the switch, a thermostat and apparatus controlled thereby for controlling the said switch control apparatus operating the same to maintain the switch open to actuation by gravity upon certain low degree of temperature.

15. In a fuel burner for steam boilers and the like, the combination with the boiler, of a casing providing a chamber, a nozzle at the forward end of the chamber for discharging fuel oil to beneath the boiler to heat the water therein, a fuel conduit having a material portion thereof within the chamber and connected with the nozzle, means connecting the chamber with the water space of the boiler permitting a flow of water from the chamber to the boiler and from the boiler to the chamber, and automatic means actuated through increase of pressure in the water chamber to predetermined extent to cause cessation of flow of oil in the oil conduit and, upon pressure in the water chamber decreasing to a predetermined extent, to cause oil to flow in the oil conduit.

16. In an oil burner for furnaces having

a water space, a casing having a chamber, an oil conduit having a portion thereof enclosed within the chamber, a nozzle in the wall of the chamber through which oil may be discharged from the conduit, a water supply line leading to and from the chamber and connected with the water space of the furnace, a pilot light for the burner positioned to heat the water conduit to maintain the temperature of the water in the chamber practically constant, electrically operated means for supplying oil to the conduit, an electric circuit therefor, a switch in the circuit for opening and closing the same, and automatic means actuated through a decrease in water pressure to close the switch and through the increase in water pressure to open the switch.

17. In an oil burner for heating systems, the combination with the boiler, of a burner for heating the water of the boiler comprising a casing having a chamber, a discharge nozzle in the wall of the chamber for the ejection of fuel, an oil conduit having a portion thereof lying within the chamber and connected with the nozzle, the chamber being closed to the nozzle, means providing for a flow of water from the boiler to the chamber and thence to the boiler to cool the front wall of the said chamber and to preheat the oil discharged through the nozzle in the said wall, and means subject to the pressure of water in the chamber produced by the boiler pressure adapted to control the supply of oil to the nozzle.

18. In an oil burner for the heating of

steam boilers etc., the combination with a boiler, of a burner member comprising a casing having a chamber, an intake line for the chamber connected with the lower part of the water space of the boiler, an outlet line for the chamber connected with the water space above the first named line, a nozzle in the forward wall of the chamber, a fuel line discharging through the nozzle, and means controlled by a pressure of water in the chamber for controlling the flow of fuel in the fuel line.

19. In an oil burner for steam boilers and the like, a casing having a chamber at its forward end, an oil discharge nozzle in the front wall of the chamber, a fuel line, the major portion of which is in the form of a coil housed in the chamber and discharging through the nozzle, a conduit leading to said chamber, a conduit leading from said chamber, both said conduits opening to the water space of the boiler providing for flow of water through the chamber, means for discharging oil under pressure through the said oil line, and mechanism carried by the casing at the rear of said chamber subject to pressure of the water in the chamber and adapted to control the discharge of oil whereby on certain high pressure in the boiler, the fuel oil ceases to be discharged and upon certain decrease of pressure the oil is caused to be discharged.

In testimony whereof I sign this specification.

DORR R. MARTIN.
